LAWRENCE C. F. HORLE, OF NEWARK, NEW JERSEY, ASSIGNOR TO FEDERAL TELEPHONE MANUFACTURING CORPORATION, OF BUFFALO, NEW YORK, A CORPORATION OF NEW YORK.

NEUTRALIZED AMPLIFIER SYSTEM.

Application filed April 24, 1925. Serial No. 25,490.

To all whom it may concern:

Be it known that I, LAWRENCE C. F. HORLE, a citizen of the United States, and a resident of Newark, county of Essex, and State of New Jersey, have invented certain new and useful Improvements in Neutralized Amplifier Systems, of which the following is a specification.

This invention relates to the control and suppression of feed-backs, or reaction currents, in electrical systems, and particularly to the neutralization, to any desired degree, in amplifier circuits comprising interlinked grid and plate circuits of a tube, of the inherent grid plate capacity coupling through which the plate circuit reacts on the grid circuit to produce disturbing oscillations.

As is well known, the control, or the neutralizing to any desired degree, of undesirable regeneration effects in amplified circuits employing the three electrode tube may be accomplished by a large variety of adaptations of the Wheatstone bridge principle. In these adaptations, certain circuit elements of the amplifier system constitute the four arms of the bridge. One of the arms comprises the capacity which is to be wholly or partially neutralized, this being the inherent capacity coupling between the grid and plate circuits of a tube. The other arms may also be substantially capacitive, or certain of the arms may be partly or wholly made up of inductance elements, the four arms being arranged to operate as a bridge system in connection with other elements of the amplifier circuits.

In one of these many possible combinations of amplifier circuit elements in a Wheatstone bridge arrangement, two of the arms are substantially capacitive and two substantially inductive. Of the two capacitive arms one comprises the inherent grid plate capacity; the other comprises the inherent grid filament capacity. The said grid filament capacity may be supplemented by a condenser connected across grid and filament. The inductive arms comprise inductive elements connected across plate and filament.

In order to secure effective and substantially uniform neutralizing action over a wide range of frequencies and under varying operating conditions in an amplifying system embodying the above cited arrange-

ment of a bridge structure comprising two substantially capacitive and two substantially inductive arms, provision must be made in the circuit connections to minimize or annul the disturbances due in general to stray capacities which act in such a manner as to introduce reactions tending to destroy or render difficult and uncertain the balance of the bridge. To avoid these disturbances due to stray capacities in various parts of the system, certain elements in said system must be maintained at the same potential, as by grounding said elements to some common convenient mass comprised in the system, such, for example, as a frame element, or frame elements, which in turn may be connected to earth if desired. The circuit elements in connection with which the matter of grounding, or defining of potentials, for the purpose of avoiding capacity disturbances assumes first importance comprise input and output circuits, movable members of tuning elements if tuned circuits are employed, and current sources such as the cathode battery or other current supply means and mechanism.

Of the above mentioned amplifier elements, the cathode current source in any given system is ordinarily and preferably so located that one of its terminals is grounded, as on a convenient mass such as a frame element forming a fixed part of the system, and such usual grounding of the cathode current source is provided in the circuit arrangements embodying the present invention. But in order to avoid disturbances due to stray capacities above referred to, it is necessary that one side also of both the input and output circuits of a given tube be brought to the same potential as the frame element or other convenient mass to which one terminal of the cathode battery is connected. Such grounding is necessary whether these circuits are tuned or untuned. In untuned circuits the grounding is required because the said disturbing effects of stray capacity in and about windings and connections appear when said circuits are left ungrounded. If the circuits are tuned, the grounding of one side is necessary not only for the reason above cited in the case of an untuned circuit, but also for the further reason that any tuning element comprised in these circuits, for example, a tun-

ing condenser, necessarily has a movable member which is manually operated and which, therefore, will be subject to disturbances due to hand capacity if the circuit which it tunes is left ungrounded.

It is required, therefore, that one side of these circuits be grounded to the common grounding mass on which the said current source is also grounded. It is, however, evident that, for a given tube, the input circuit and the output circuit cannot terminate on the same corners of the bridge. Therefore if one of these circuits, e. g., the input circuit, is conductively coupled to the tube elements, and grounded on one side to the frame or other mass to which the current source is also grounded, then neither side of the other, or output, circuit of the given tube can be grounded if said output circuit is at the same time conductively coupled to the tube elements, and special means are required for the grounding of the said output circuit.

Further, in a bridge system of the type described herein, the input circuit is coupled across a corner intermediate the two capacitive arms and a corner intermediate the two inductive arms. Therefore in order to permit the grounding of one side of the input circuit to the common grounding mass on which the cathode current source is grounded when the said input circuit is conductively coupled to the bridge corners, the cathode current source must also be connected to the bridge corner intermediate the two inductive arms of the bridge. Means must therefore be provided in that inductive bridge arm which is between the cathode and the corner intermediate cathode and anode, whereby heating current from said current source may be conducted to the cathode through said arm.

For convenience in exposition, the amplifier system to which the bridge arrangement is adapted has been stated herein to comprise a single three electrode thermionic device with its related circuits. It is to be understood, however, that the invention is directed not only to such single stage system but also to a multi-stage system. The same difficulties involved in the adaptation of the above mentioned bridge to the single stage amplifier are encountered to the same or greater degree in the case of a multi-stage, for reasons which will be readily apparent.

In order to meet the problems above outlined there is provided in accordance with the present invention an improved circuit arrangement for an amplifier system embodying a Wheatstone bridge structure of the type stated, whereby disturbing capacity effects may be avoided, said circuit arrangement providing for the grounding, preferably to the common grounding mass, such as a frame element or elements, on which the

cathode current source is grounded, of one side of the input circuit or circuits, of the thermionic device, or devices. Said circuit arrangements further provide for similar grounding of the output circuit or circuits, and in case any or all said input and output circuits are tuned, for the similar grounding of the movable members of tuning condensers or other tuning elements.

In general the invention provides for an effective disposition of the various elements of the system and particularly for the defining of the potential of certain elements with reference to a common grounding mass comprised in the system, and a resultant minimizing of disturbing current reactions such as those due to stray capacities, so that an amplifier embodying the well known bridge arrangement herein described may be easily and economically constructed and may be operated with high efficiency over a wide range of frequencies, without disturbing effects due to undesirable cathode circuit to anode circuit reactions.

The circuit arrangement employed in carrying my invention into effect, and its principle of operation, will be clearly understood by reference to the following description, and the accompanying drawings.

Fig. 1 shows diagrammatically an embodiment of the invention in a single stage amplifier system comprising a vacuum tube with the usual three electrodes, grid, plate and filament.

Fig. 2 illustrates a two-capacitive arm, two-inductive arm bridge arrangement in an amplifier system. The circuits shown in Figures 1 and 2 are identical, but for clearness the circuits are arranged in bridge form in Fig. 2, and in the conventional radio circuit diagram form in Fig. 1.

Fig. 3 illustrates an amplifier system embodying the invention and comprising a plurality of tubes.

Referring to Fig. 1, vacuum tube 1 comprises filament 2, grid 3 and plate 4. Grid 3 is connected in an input circuit 5, one side of which is grounded to a convenient mass such as a frame element 24 and which may be tuned by variable condenser 6 of which the side 7 will be considered the rotor. Plate 4 is connected in a plate-filament circuit 8, comprising, in series, coil 9 and inductive element 10. Inductive element 10 is composed of the two preferably closely coupled coils 11 and 12. Filament battery 13 and rheostat 14 are connected to the filament through the said coils 11 and 12. Plate battery 15 is connected into the plate filament circuit, preferably between coils 9 and 11. This battery may also be connected between coils 9 and 12. Condenser 16 is connected across filament 2 and grid 3. Condensers 17 and 18, shown in dotted line, represent respectively the inherent capacity

between grid and plate circuits and between grid and filament. The plate filament circuit 8 is inductively coupled to an output circuit 19, one side of which is grounded as to a frame element 24^a and which comprises coils 20 and 21, coupled with a coil 9 and inductive element 10. The circuit 19 may be tuned as by a variable condenser 22 of which the side 23 is to be considered 10 the rotor. Rotor 7, of condenser 6, and battery 13 are grounded to a convenient mass such as the frame element 24. Likewise rotor 23, of condenser 22, is grounded as to frame element 24^a. Radio frequency by-pass condensers 25 may be included, as shown in the figures, if desired.

In operation, incoming signals from any outside source are impressed, by way of the input circuit 5, between grid and filament, 20 and the resultant amplified voltage in the plate circuit is impressed on the output circuit 19. Oscillations due to feed-back from plate-filament circuit 8 to grid-filament circuit 5, through the electrostatic coupling 25 formed by the inherent capacity 17 between grid and plate circuits, are controlled or neutralized by the balanced bridge action incorporated in the system. The bridge action of the circuits is obvious from an inspection of Fig. 2. The four arms of the bridge are seen by reference to the said Fig. 2 to comprise; inherent grid-plate circuit capacity 17 (the capacity coupling through which the undesirable feed-back takes place), 30 between the corners G and P; inherent grid-filament capacity 18 together with additional grid-filament capacity, which may be added, in the form of condenser 16, between corners G and F; the impedance comprising 35 coil 9, between corners P and X; and the impedance comprising inductive element 10 made up of the two coils 11 and 12, between corners F and X. Since capacities 17 and 40 18 are fixed for any given type of tube, the balance of the bridge is determined by the proper proportioning of the impedances between the corners P and X and between the corners F and X, and of the condenser 16 if 45 used.

50 Referring to Fig. 3, the operation as described for Fig. 1 is essentially the same for the system comprising a plurality of tubes, it being understood that the amplified output of tube 1 (Fig. 3) is impressed on the input of a second tube 26. The inductively coupled output circuit 19 of tube 1 preferably constitutes the input circuit of this second tube. The anode-cathode circuit 27 of tube 26 is arranged in the same manner 55 as described in connection with anode-cathode circuit 8 of tube 1, and the placing of current sources, cathode, coil windings and grounds is the same as in the case of corresponding elements about the first tube 60 of the series. Circuit 27 may be coupled to

the input circuit of a succeeding tube (not shown). Input circuits 5, 19, 28 are grounded to a common convenient grounding mass such as a frame element or frame elements of the system, as 29. Likewise one terminal of 70 the cathode battery 13 (Fig. 3) is grounded to such frame element, as at 29^a. Radio frequency by-pass condensers as 30 are preferably provided in the anode-cathode circuits. 75

The well understood action of the simple bridge arrangement of the type herein described is seen to be in no wise complicated by reason of its adaptation to amplifier circuits, and it is evident that no difficulties arise in the proportioning of the amplifier elements making up the respective arms of the bridge or in securing the desired complete or partial balance of the bridge system. Certain serious difficulties, however, are encountered, as before suggested, in the adapting of this type of bridge to the vacuum tube amplifier, due to the complexity of structure and the exacting requirements as to the relation of various elements to each other and to ground in an amplifier system as compared with the usually simple form of the Wheatstone bridge proper. How the complete amplifier system which embodies the present invention is developed in such a manner on the simple two capacitive arm, two inductive arm bridge as to meet these difficulties is best explained by referring again to Fig. 2. As before stated, one side of both input and output circuits of a given tube are required to be grounded to a common grounding mass such as a frame element of the system, with the movable member of the tuning element, if the circuit is tuned, connected to the grounded side. At the same time the said circuits necessarily must terminate on, or be coupled across, different corners of the bridge. In order to meet this difficulty, in the present invention I arrange to connect one of the circuits—the input circuit 5 terminating on points G and X—conductively into the system as usual, and to ground one side of this circuit 5, and if the circuit is tuned, the movable member 7 of any tuning element such as condenser 6, as at frame element 24. 115 But I arrange the other circuit in such relation to the system that it is conductively separated off from the bridge structure of the preceding tube and then grounded on one side, with the movable member of any tuning element connected therewith also grounded. This necessary conductive separating off of the circuit which is on the output side of a given tube, and which contains a movable element also requiring grounding 120 if the circuit is tuned, is accomplished by the provision of the extra winding comprised in coils 20 and 21, this winding being inductively coupled with the series coils 9 and 10 of plate circuit 8. The resulting con- 130

ductively isolated but inductively coupled circuit 19 is then grounded on one side as to a frame element at 24^a. If the output circuit is tuned, as by condenser 22, the movable member 23 of this tuning element is also grounded by reason of its connection to the grounded side of the circuit.

It will be noted that to provide this conductive separating off of the circuit 19 on the output side of a given amplifier tube, advantage is taken of the fact that in the two capacitive arm, two inductive arm bridge system herein used for the purpose of controlling or balancing out feed-backs, the two arms between points P and F through X, to which points the output circuit of the tube is coupled, are the inductive arms of the bridge, in series. Therefore, it becomes possible to utilize these arms comprising coils 9 and 10 in the inductive coupling with the isolated and separately grounded tuned circuit 19. In effect the inductive arms 9 and 10 of the bridge become the primary of a coupling transformer of which the windings 20 and 21 constitute the secondary.

Further, as before explained another difficulty arises in the adaptation of this simple bridge to the three-electrode vacuum tube amplifier system. This difficulty involves the necessary placing of the cathode current source at the corner of the bridge intermediate the cathode and anode, this placing being required in order to permit the simultaneous grounding of one side of the conductively coupled input circuit and a terminal of the cathode battery to the common grounding mass. The problem is met in the present invention by arranging the circuits in such a manner that the cathode as a whole is at a potential different from ground (i. e., "off ground") or different from the potential of either terminal of the cathode current source. The cathode is removed from such ground or current source potential by the inductive element (10) forming or comprised in one of the bridge arms. This element extends from the cathode corner of the bridge to the corner intermediate the cathode and anode. The cathode current source, with one terminal grounded to some common mass such as a frame element, is connected into the system at said corner which is intermediate the two inductive arms of the bridge. In order to provide a path from the said current source to the cathode, the said inductive element is constructed in the form of two coils, conductively separated but inductively coupled. For this two-winding construction of the inductive element 10, use is preferably made of the duplex-wound coil which forms part of the subject-matter of my copending application Ser. No. 614608, filed January 24, 1923. It is to be understood, however, that

said inductive element 10 is not restricted in its construction to the form described in said copending application, as other forms of coupled coils may be utilized for the purpose of the present invention.

Filament battery 13, or other current source, is thus not connected directly across filament 2, as this placing would result in separating the battery from grounding mass 24 by one of the inductive arms (10) of the bridge. Utilizing the two-winding element 10, the battery 13 is connected to the filament through the two coils 11 and 12 which constitute said inductive element. Since one side of input circuit 5 is connected also to coil 12 and at the end of said coil farthest from the filament (point X of the bridge) and since, further, this side of the input circuit is grounded (as at grounding mass 24), therefore, this method of connecting the input circuit 5 and the filament battery 13 brings one end of said battery to the potential of the grounding mass 24, also to the potential of one side of the input circuit, and too that of the movable member of the tuning element if this circuit is tuned. It

is to be noted from the above description that in the circuit arrangement for cathode current source connections herein disclosed, a cathode current, for example, a direct current provided by a battery or a heating current of any suitable character from any source, is carried from the current source to the cathode over conductive elements which in themselves are primarily inductive elements forming a radio frequency inductance common to the cathode-anode circuit and the cathode-control electrode circuit.

It is obvious that the balancing of the bridge system for alternating current is not appreciably affected by the substitution of the two-winding inductive element 10 for a single wound coil, since the coils 11 and 12 are preferably closely coupled with a degree of coupling, by reason of their method of construction, practically unity.

It is to be noted further that by the above described placing of battery 13, utilizing the two-winding inductive element 10 to locate said battery 13 between the two inductance arms of the bridge instead of at the filament end of these arms in series, it is possible to place the plate battery 15 adjacent the filament battery 13, as in usual practice. In the present embodiment plate battery 15, is conveniently placed between coils 9 and 11.

It will be apparent from the foregoing discussion of the circuit arrangements disclosed in the present invention for the purpose of adapting the two capacitive arm, two inductance arms bridge to amplifier use, that proper grounding of an input circuit and at the same time of current sources to some common grounding mass such as a frame element of the system is accomplished, in

general terms, by locating the cathode "off-ground," thereby permitting the establishing as a ground point for the bridge of that corner of said bridge which is between the 5 two inductive arms.

As applied to an amplifier including a three-electrode vacuum tube of well known type and operating on the frequencies usual in radio telephony, I find that dimensions 10 for various elements of the system herein described which have given efficient results in operation, are as stated below. Coil 9 is of nine turns $3\frac{1}{4}$ " diameter. Double wound coil 10 (made up of the two coils 11 and 12) 15 is of three double turns, $3\frac{1}{4}$ " diameter. Close paralleling of the turns makes the coupling between coils 11 and 12 substantially unity. Coils 20 and 21 are arranged as a single coil of 54 turns, 3" diameter. 20 This 54 turn coil, constituting coils 20 and 21 of the figures, is preferably loosely coupled to coils 9 and 10. Condenser 16 if used is preferably of a form which permits close adjustment for a final setting of the 25 bridge for the purpose of neutralizing feed-back, the condenser 16 then being locked for this setting. An appropriate capacity range for this condenser 16 is from 20 mmfd. to 35 mmfd. In describing the circuits 5 and 30 19, I have shown optional tuning means as comprising condensers 6 and 22 with manually movable rotors. It is to be understood that these well known tuning means may be replaced by any other which will accomplish 35 the purpose of tuning the said circuits 5 and 19. The tuning condensers 6 and 22 or other equivalent means, form no part of the present invention and require no detailed description as to arrangement or magnitudes. 40 In the description of the invention reference has been made to a three electrode vacuum tube comprising grid, plate and filament. This invention, however, is not to be understood as limited in its applications to 45 amplifier or other systems comprising said three-electrode vacuum tube, since it is evident that thermionic devices of various types may be used comprising anode, cathode and control electrode elements. 50 In illustrating the invention I have shown 55 embodiments thereof applied to single or multi-stage amplifiers as employed in radio receiving systems, particularly for radio frequency amplification. It will be apparent, however, that the invention may be extended to many other applications. Circuit arrangements in accordance with the invention may be applied, for example, to systems comprising radio-frequency amplifiers arranged in bridge form as herein described, and also comprising other amplifiers not arranged in the said bridge form. Said circuit arrangements may likewise be applied to audio-frequency amplifiers; or to 60 radio transmitting apparatus; or to line 65

wire transmitting and receiving apparatus; or to devices for the prevention of radiation from the antennas of radio receiving systems. It is evident that these and still further applications of the invention other than 70 those of the embodiments shown may be made, and that various modifications in the circuit arrangements and apparatus employed may also be made, without departing from the scope of the invention as set 75 forth in the appended claims.

What is claimed is:

1. In an electrical system comprising a thermionic device having a control electrode, an anode and a cathode, an input circuit including the control electrode and the cathode, a circuit including the anode and the cathode, a frame element for said system, said electrical system being arranged as a bridge for the controlling of feed-back action from the 80 anode-cathode circuit to the input circuit, said bridge comprising two inductive arms included in said anode-cathode circuit, and means for grounding said bridge to said frame element at a point intermediate said 85 inductive bridge arms.

2. In an electrical system comprising a thermionic device having a control electrode, an anode and a cathode, an input circuit including the control electrode and the cathode, a circuit including the anode and the cathode, a frame element for said system, a current source for the cathode, said current source being grounded to the frame element, said electrical system being arranged as a 90 bridge for the controlling of feed-back action from the anode-cathode circuit to the input circuit, said bridge comprising an inductive arm between said cathode and a bridge corner intermediate said cathode and 95 anode, said bridge being grounded to said frame element at said corner, and means comprising said inductive arm for maintaining said cathode at a potential different from that of said frame element.

3. In an electrical system comprising a thermionic device having a control electrode, an anode and a cathode, an input circuit including the control electrode and the cathode, a circuit including the anode and the cathode, said electrical system being arranged as a bridge for the controlling of feed-back action from the anode-cathode circuit to the input circuit, said bridge comprising an inductive arm having two inductively coupled windings and located between 115 said cathode and a bridge corner intermediate said cathode and anode, a current source for the cathode, and means comprising said inductive arm for conducting heating current from said current source to said cathode and simultaneously for conducting radio frequency oscillations in said anode-cathode circuit.

4. In an electrical system comprising a 120

thermionic device having a control electrode, an anode and a cathode, an input circuit including the control electrode and the cathode, a circuit including the anode and the cathode, said electrical system being arranged as a bridge for the control of feed-back action from the anode-cathode circuit to the input circuit, said bridge comprising an inductive arm included in said anode-cathode circuit and having two inductively coupled windings, one of said windings being included in said input circuit, a current source for the cathode, and means including said windings for bringing one side of said input circuit and a terminal of the said current source to the same potential and to a potential substantially different from that of the cathode.

5. In an electrical system comprising a thermionic device having a control electrode, an anode and a cathode, an input circuit including the control electrode and the cathode, a circuit including the anode and the cathode, a frame element for the system, said system being arranged as a bridge for the control of feed-back action from the anode-cathode circuit to the input circuit, the anode-cathode circuit comprising two inductive bridge arms, one of said two arms having two inductively coupled windings, one of said windings being included in said input circuit, tuning means for the input circuit comprising a tuning element having an adjustable member, a current source for the cathode, a circuit inductively coupled to the anode-cathode circuit and having one side grounded to said frame element and comprising a tuning element having its adjustable member grounded to said frame element, and means including said windings for bringing one side of the said input circuit and the said adjustable member of the input circuit tuning element and one terminal of the said current source to the potential of said frame element and to a potential substantially different from that of the cathode.

6. In an amplifier, a three-electrode thermionic device comprising an anode, a cathode, and a control electrode, input and anode-cathode circuits for said amplifier, said amplifier being arranged in balanced bridge form for controlling feed-back action from the anode-cathode circuit to the input circuit, one of the arms of said bridge being inductive and included in said anode-cathode circuit and having two inductively coupled windings, a current source for the cathode, and means comprising said inductive arm for bringing one side of said input circuit and one terminal of said current source to the same potential, one of said windings being connected directly in said input circuit, both said windings being connected between said current source and said cathode.

7. In an amplifier, a three-electrode thermionic device comprising an anode, a cathode and a control electrode, input and anode-cathode circuits for said amplifier, a frame element for said amplifier, said amplifier being arranged in balanced bridge form for controlling feed-back action from the anode-cathode circuit to the input circuit, two of the arms of said bridge being inductive and included in said anode-cathode circuit, one of said two arms being located between the cathode and an adjacent corner of the bridge and having two inductively coupled windings, a current source for the cathode, a circuit inductively coupled to the anode-cathode circuit, one side of said inductively coupled circuit being grounded to said frame element, and means comprising said windings for bringing one side of said input circuit and one terminal of said current source to the potential of said frame element, one of said windings being connected directly in said input circuit, both said windings being connected between said current source and said cathode

8. In an electrical system comprising a thermionic device having a control electrode, an anode and a cathode, a tuned input circuit including the control electrode and the cathode, a circuit including the anode and the cathode, said electrical system being arranged as a bridge for the control of feed-back action from the anode-cathode circuit to the input circuit, said bridge comprising an inductive arm having two inductively coupled windings, one of said windings being included in said input circuit, tuning means for the input circuit comprising a tuning element having an adjustable member, a current source for the cathode, and means comprising said windings for bringing the said adjustable member and one terminal of the said current source to the same potential and to a potential substantially different from that of the cathode.

9. In an electrical system comprising a thermionic device having a control electrode, an anode and a cathode, a tuned input circuit including the control electrode and the cathode, a circuit including the anode and the cathode, a frame element for the system, said system being arranged as a bridge for the control of feed-back action from the anode-cathode circuit to the input circuit, the anode-cathode circuit comprising two inductive bridge arms, one of said two arms being connected to the cathode and extending to an adjacent bridge corner intermediate cathode and anode and having two inductively coupled windings, tuning means for the input circuit comprising a tuning element having an adjustable member, a current source for the cathode, a tuned circuit inductively coupled to the anode-cathode circuit and having one side grounded to said

- frame element and comprising a tuning element having its adjustable member grounded to said frame element, and means comprising said windings, for bringing one side 5 of the said input circuit and the said adjustable member of the said input circuit tuning element and one terminal of the said current source to the potential of said frame element and to a potential substantially different from that of the cathode.
10. In an amplifier, a three-electrode thermionic device comprising an anode, a cathode, and a control electrode, input and anode-cathode circuits for said amplifier, said amplifier being arranged in balanced bridge form for controlling feed-back action from the anode-cathode circuit to the input circuit, one of the arms of said bridge being inductive and included in said anode-cathode circuit and having two inductively coupled windings, tuning means for said input circuit comprising a tuning element having an adjustable member, a current source for the cathode, and means comprising said 15 inductive arm for bringing said adjustable member and one terminal of said current source to the same potential, one of said windings being connected directly in said input circuit, both said windings being connected between said current source and said cathode.
- 20
- 25
- 30
11. In an amplifier, a three-electrode thermionic device comprising an anode, a cathode and a control electrode, input and anode-cathode circuits for said amplifier, 35 said amplifier being arranged in balanced bridge form for controlling feed-back action from the anode-cathode circuit to the input circuit, two of the arms of said bridge being inductive and included in said anode-cathode circuit, one of said two arms being located between the cathode and an adjacent corner of the bridge and having two inductively coupled windings, tuning means for said input circuit comprising a tuning element having an adjustable member, a current source for the cathode, a tuned circuit inductively coupled to the anode-cathode circuit and comprising a tuning element having an adjustable member at ground potential, 40 and means comprising said windings for bringing said adjustable member of the said input circuit tuning element and one terminal of said current source to ground potential, one of said windings being connected directly in said input circuit, both said windings being connected between said current source and said cathode.
